PORTABLE MORTAR

Raymond Posey, United States Marine Corps

Application June 26, 1951, Serial No. 233,672

8 Claims. (Cl. 89—1)

(Granted under the act of March 3, 1883, as
amended April 30, 1928; 370 O. G. 757)

1

The invention described herein may be manufactured and used by or for the Government of the United States of America for governmental purposes without the payment of any royalties thereon or therefor.

The invention relates to a mortar or the like firearm and more particularly to a light-weight, highly mobile, hand-held mortar.

The mortar of the present invention fires standard ammunition, is simple and economical in construction, can be quickly assembled and disassembled and can be aimed either directly at the target or indirectly between the approximate limits of 5° and 85° of elevation. For this purpose a suitable sight may be provided on the muzzle half of the barrel.

The elongated bottom of the base cap of the mortar provides a firing mechanism housing which contains the continuous pull firing mechanism which is semi-automatic and is operated by a trigger or firing lever. The housing encloses the entire firing mechanism and protects it from damage and prevents the entrance of mud and water.

The location of the trigger or firing lever is at a point intermediate the ends of the barrel of the mortar and spaced a substantial distance in advance of the firing mechanism housing. This provides for a steadier and more natural firing position to be assumed by the gunner than in known mortars in which the trigger is located adjacent the base of the mortar. This is true for all positions and angles from which the mortar is fired. The advanced location of the trigger or firing lever on the barrel allows the trigger hand of the gunner to assist in holding and steadyng the mortar. When firing at a high angle from soft ground the base plate of the mortar tends to sink further into the ground with the firing of each round. The advanced location of the trigger lever on the barrel substantially prevents the mortar being rendered inoperative by sinking into soft ground, which frequently occurs with known mortars having the trigger near the base.

The trigger lever is designed to be operated by engaging it with several fingers of the hand instead of by a single finger.

Connection between the firing lever or trigger and the firing mechanism is provided by a connecting rod, having a casing or housing therefor.

A hand guard is provided on the connecting rod casing and facilitates the actuation of the trigger and the firing of the weapon. A folding carrying handle is also mounted on the connecting rod casing. This is important particularly when the mortar tube is too hot from firing to grasp in

2

the hands for carrying. When not in use, the handle can be folded against the barrel of the weapon. A rectangular curved base plate is provided strengthened by ribs on the under side, and longer on one side to facilitate seating when firing at low angles.

An object of the invention is the provision of a reliable and durable light-weight, mobile hand-held mortar.

Another object is to provide a mortar of simple and economical construction which can be readily assembled and disassembled without need of tools.

A further object is the provision of a firing mechanism housing at the base of the mortar which will enclose the entire firing mechanism and protect it from damage and prevent the entrance of mud and water.

Another object is to provide for a steady and natural firing position to be assumed by the gunner, and to enable the gunner's trigger hand to assist in holding and steadyng the mortar and to enable the gunner to engage and operate the trigger lever with several fingers of his hand.

Another object is to provide means for readily holding and transporting the portable mortar particularly when the barrel has become hot from firing.

Another object is the provision of a novel and efficient firing mechanism which is dependable and of rugged construction and easily assembled and disassembled.

Other objects and many of the attendant advantages of this invention will be readily appreciated as the same becomes better understood by reference to the exemplary embodiment set forth in the following description when considered in connection with the accompanying drawings wherein:

Fig. 1 is a top plan view of a mortar embodying the invention.

Fig. 2 is an elevation of the mortar.

Fig. 3 is a fragmentary sectional elevation of a rearward portion of the mortar shown in Fig. 2, with the firing mechanism in retracted position ready to fire.

Fig. 4 is a fragmentary sectional elevation of a forward portion of the mortar shown in Fig. 2, and showing the parts in retracted position ready to fire.

Fig. 5 is sectional view substantially on the line 5—5 of Fig. 2.

Fig. 6 is sectional view substantially on the line 6—6 of Fig. 2.

Fig. 7 is a fragmentary partly sectional view showing the trigger cam and connecting rod cam in retracted position ready to operate for firing.

Fig. 8 is a top view of the striker and firing pin. Fig. 9 is top view of the sear cam.

Referring to the drawings, a portable mortar embodying the invention is shown, and is provided with a tube or barrel 2 and a base cap and firing mechanism housing 1 threadedly mounted on the barrel at the rear thereof, and having a firing mechanism housing cover and gasket 3.

A trigger or firing lever 14 is pivotally mounted at 22 to the forward end of a firing lever and connecting rod housing 13 which is connected to the firing mechanism housing and extends forwardly along the barrel 2 a substantial distance to an advanced point intermediate the ends of the barrel. The housing 13 is secured to the barrel 2 at said advanced location by means of a tube bracket 18.

The trigger or firing lever has an arm 21 which has a cam end engaging a connecting rod cam or plug 17 which is threaded into the end of the connecting rod 16. A slot 26 is provided in the connecting rod and receives the trigger arm 21. A trigger lock is provided at 15.

The connecting rod 16 is tubular at its forward portion providing a longitudinal bore and houses a retracting spring 27 which engages at one end with a wall 77 of the rod 16. At its other end the spring 27 engages a plunger 28 which in turn engages a plunger retaining or bearing pin 29 fixed in the connecting rod housing 13 and extending through the slot 26 in the connecting rod 16.

The connecting rod 16 extends through the tubular housing 13 and into connection at its rear end with the firing mechanism within the cover 3.

The rear end of the connecting rod 16 is connected to a sear cam actuator 68 by means of an actuator plunger 71 received in the sear cam actuator pin 69 and pressed by spring 72. The actuator plunger 72 is received within an opening 13 in the rear end of the connecting rod.

The sear cam actuator pin 69 is received within an opening 58 in the sear cam 55 whereby the sear cam is moved in accordance with movement of the firing lever connecting rod 16.

The sear cam 55 is slidably received within a striker 49 which is slotted longitudinally as seen at 53 and 78 in Fig. 8 to permit relative movement. The slot in the striker 49 at its lower side terminates rearwardly in a shoulder 52 which is engaged by the actuator pin 69 upon rearward movement thereof to retract the striker. The striker 49 carries the firing pin 48 which is disposed to pass through opening 47 of the firing pin guide and ignition cartridge seat 45.

The striker is provided with a sear notch or seat, as indicated at 54, which is designed to receive the sear 64 which is slidably mounted and urged into engagement with the sear seat 54 of the striker by means of sear spring 66 disposed between the sear 64 and a sear spring cap 67.

The sear cam 55 is guided at its rear end by a sear cam guide 61 retained on the sear cam by means of a retaining pin 62. A main spring 60 is disposed between the sear cam guide 61 and the end of the striker 49.

An adapter 4 is threaded onto the rear end of the firing mechanism housing 1, and a carrying strap ring 10 and a circular nut 6 are received on the adapter and retained thereon by a spherical projection member 5 which has a tubular portion threaded into the adapter 4. A socket member 7 carrying a base plate 8 having strengthening rib means 9 is threaded onto the circular nut 6. The base plate is curved and generally rectangular and longer on one side to facilitate seating.

A hand guard 12 is mounted on the connecting rod housing 13 and is disposed adjacent to the firing lever 14 and facilitates the actuation of the trigger and the firing of the weapon.

A folding carrying handle 11 is also mounted on the connecting rod housing 13 and as shown particularly in Fig. 6 may be rotated to folded position against the barrel 2 when not in use and to be out of the way when firing the mortar. The folding handle is of particular value in transporting the mortar after it has become hot from firing.

Operation

The advanced location of the firing lever or trigger 14 at a point intermediate the ends of the mortar barrel or tube 2 and spaced a material distance in advance of the firing mechanism housing and base of the mortar provides for a steady and natural firing position to be assumed by the gunner, and enables the trigger hand of the gunner to assist in holding and steadyng the mortar and enables the gunner to engage and operate the trigger lever with several fingers of his hand. In firing high angle fire from soft ground the advanced location of the trigger lever on the barrel prevents the mortar being rendered inoperative by sinking of the base plate into the ground.

When the trigger or firing lever 14 is pressed, it draws the connecting rod 16, actuator 68, and sear cam 55 forward, and at the same time, compresses coil springs 27 and 60, until the slope 55 of the sear cam 55 engages the nose of the sear 64. This provides the first pull or resistance on the trigger lever. As pressure is continued to be applied to the firing lever 14, the slope 55 of the sear cam is drawn still further under the nose or end of the sear 64 and raises the sear until the end of the sear disengages from its seat 54 on the striker 49. This allows the striker 49 with the firing pin 48 to be driven forward by the compressed coil spring 60. In the completion of this motion the sear 64 is held upward by the elongated surface 51 of the sear cam 55 and the firing pin 48 passes through the hole 47 in the firing pin guide 45 of the barrel cap 1 and strikes the primer of the ignition cartridge of the shell and discharges the cartridge in the firing chamber of the barrel. As the firing pin 48 reaches its full forward position, its shoulder comes against its seat 46 on the forward wall of the housing 1 thereby stopping the forward travel of the firing pin.

On release of the trigger 14, the entire mechanism returns automatically to its rearward position. The coil spring 27 in the tube of the connecting rod 16, being still compressed, is now free to drive it and the actuator 68, sear cam 55 and its guide 61, to the rear. When the sear cam actuator pin 69 of actuator 68 reaches the shoulder 52 at the rear end of the slot 53 in the striker 49, it engages the shoulder 52 and moves the striker rearwardly until the spring pressed sear 64 snaps back into its seat 54 on the striker in position for firing.

A semi-automatic firing mechanism is provided which is of simple, rugged construction, dependable in operation, and which is designed to be readily assembled and disassembled.

Adjacent the forward end of the barrel or tube 2 of the mortar is a suitable bracket 20 providing a mounting for one end of a carrying strap 19, the other end of which is received in the carrying strap ring 10. A suitable sight 20a is desirably mounted on the bracket 20.

Obviously many modifications and variations of the present invention are possible in the light of the above teachings. It is therefore to be understood that within the scope of the appended claims the invention may be practiced otherwise than as specifically described.

What is claimed is:

1. In combination in a mortar or the like firearm having a barrel and a firing mechanism housing secured to the barrel, a striker with firing pin and spring mounted in said housing, a sear and means urging the sear into engagement with the striker, movably mounted means for releasing said sear, a connecting rod disposed laterally of and parallel to said barrel and connected at one end to said movably mounted sear releasing means, said connecting rod being of a length extending forwardly a substantial distance along said barrel, means mounting said connecting rod for longitudinal sliding movement, trigger means mounted on said barrel intermediate the ends thereof and spaced a substantial distance from said firing mechanism housing, said trigger means being in operative engagement with the forward end of said longitudinally slidable connecting rod for moving said connecting rod forwardly to move the sear releasing means for firing, and a spring mounted in engagement with said connecting rod for returning the connecting rod and sear releasing means and striker to rearward position.

2. In combination in a mortar or the like firearm having a barrel and a firing mechanism housing secured to the barrel, a striker with firing pin and spring mounted in said housing, a sear and means urging the sear into engagement with the striker, a sear cam for moving the sear out of engagement with the striker to release the striker and firing pin, sear cam actuating means including a member extending laterally from said sear cam, a connecting rod disposed laterally of and parallel to said barrel and connected at one end to said laterally extending member of said sear cam actuating means, said connecting rod being of a length extending forwardly a substantial distance along said barrel, means mounting said connecting rod for longitudinal movement, trigger means mounted on said barrel intermediate the ends thereof and spaced a substantial distance from said firing mechanism housing, said trigger means being disposed in operative engagement with the forward end of said connecting rod for moving said connecting rod forwardly to move the sear cam actuating means to actuate the sear cam for firing, and a spring mounted in engagement with said connecting rod for returning the connecting rod and sear cam actuating means and striker to rearward position.

3. In apparatus according to claim 1, an elongated trigger and connecting rod housing connected at its rear end to said firing mechanism housing and at its forward end to said barrel, said connecting rod being slidably received within said trigger and connecting rod housing and said trigger means being pivotally mounted in said housing, said connecting rod having a longitudinal bore therein, said connecting rod having a longitudinal slot therein communicating with said longitudinal bore, said trigger means comprising a lever pivoted in said trigger and connecting rod housing and having an arm extending into said slot in said connecting rod for said operative engagement therewith.

4. In apparatus according to claim 1, an elongated trigger and connecting rod housing connected at its rear end to said firing mechanism

housing and at its forward end to said barrel, said connecting rod being slidably received within said trigger and connecting rod housing and said trigger means being pivotally mounted in said housing, said connecting rod having a longitudinal bore therein, said connecting rod having a longitudinal slot therein communicating with said longitudinal bore, said trigger means comprising a lever pivoted in said trigger and connecting rod housing and having an arm extending into said slot in said connecting rod for said operative engagement therewith.

5. In apparatus according to claim 1, an elongated trigger and connecting rod housing connected at its rear end to said firing mechanism housing and at its forward end to said barrel, said connecting rod being slidably received within said trigger and connecting rod housing and said trigger means being pivotally mounted in said housing, said connecting rod having a longitudinal bore therein, said connecting rod having a longitudinal slot therein communicating with said longitudinal bore, said trigger means comprising a lever pivoted in said trigger and connecting rod housing and having an arm extending into said slot in said connecting rod for said operative engagement therewith, said longitudinal bore of said connecting rod terminating in a wall at the rear end of the bore, said spring comprising a coil disposed in said bore and seating at one end against said wall, a bearing pin fixed in said connecting rod housing and extending through said longitudinal slot in said connecting rod, said bearing pin providing a stop for the forward end of said coil spring.

6. In apparatus according to claim 1, an elongated trigger and connecting rod housing connected at its rear end to said firing mechanism housing and at its forward end to said barrel, said connecting rod being slidably received within said trigger and connecting rod housing and said trigger means being pivotally mounted in said housing, a tubular hand guard surrounding said connecting rod housing and disposed adjacent the handle arm of said trigger means to aid in the operation of said trigger means and in 50 steadying the weapon by the trigger hand of the gunner.

7. In apparatus according to claim 1, an elongated trigger and connecting rod housing connected at its rear end to said firing mechanism housing and at its forward end to said barrel, and a carrying handle rotatably mounted on said connecting rod housing for rotation between an outward carrying position and an inward folded position against the barrel to be out of the way during firing of the weapon.

8. In apparatus according to claim 2, said striker having a longitudinally extending transverse slot therethrough receiving said laterally extending member of said sear cam and permitting forward movement thereof relative to said striker, said striker having a shoulder at the rear end of its said slot disposed to be engaged by said laterally extending member of said sear cam to move the striker rearwardly upon release of the trigger and return of the sear cam to rearward position by said connecting rod spring.

RAYMOND POSEY.
